卷之二

The diagram shows a cross-section of a circular structure, possibly a wheel or drum. It features a central hub with a cross-shaped bore. Surrounding the hub are several concentric rings and a series of radial spokes or pins extending from the outer edge. Numbered labels (1 through 12) are placed around the perimeter of the structure, corresponding to specific features: 1 is at the top, 2 is on the right, 3 is on the left, 4 is at the bottom, 5 is on the right, 6 is on the left, 7 is at the top, 8 is on the right, 9 is on the left, 10 is at the top, 11 is on the right, and 12 is on the left. The structure is rendered with fine lines and cross-hatching to indicate depth and material.

Attorney

UNITED STATES PATENT OFFICE.

ARTHUR A. VARDELL, OF DALLAS, TEXAS.

DOFFER.

No. 922,545.

Specification of Letters Patent.

Patented May 25, 1909.

Application filed July 23, 1908. Serial No. 445,794.

To all whom it may concern:

Be it known that I, ARTHUR A. VARDELL, a citizen of the United States, residing at Dallas, in the county of Dallas and State of Texas, have invented certain new and useful Improvements in Doffers, of which the following is a specification.

My invention relates to apparatuses for doffing cotton from the gin saws in the process of ginning. As heretofore constructed, apparatuses of this character are open to serious objection, inasmuch as they either wear out quickly themselves or they dull and ruin the gin saws.

It is therefore, the object of my invention to provide an apparatus which will obviate these objections, including a practically indestructible doffer, which will not strike the gin saw, but which will however, readily and quickly remove the cotton therefrom in the process of ginning.

In its theoretical embodiment, my invention consists in a doffer constructed of metal throughout and formed with peripheral blades extending longitudinally thereof, having equidistantly spaced recesses. This doffer I propose to rotatively mount in close but non-contacting juxtaposition to the gin saw, with its said spaced recesses opposite the saw blades thereof, and to drive the same at a speed greatly increased over that of said gin saw, whereby the air current generated by said peripheral blades will operate to quickly and effectively remove the cotton or lint clinging to the said saw blades.

In the accompanying drawings, forming a part of this specification, Figure 1 is a view partly in side elevation and partly in longitudinal section, of my improved doffer. Fig. 2 is a view thereof, partly in end elevation and partly in vertical cross-section. Fig. 3 is an enlarged detail cross-sectional view of the peripheral plates. Fig. 4 is an enlarged detail fragmentary sectional view of one of the end plates, and, Fig. 5 is an enlarged sectional view through one of the end plate hubs.

In the practical embodiment of my invention, I provide a doffer embodying a central rotatable shaft 1, on which are mounted at spaced points, the end plates 2 of my improved doffer. Said end plates have central openings and are riveted through the material surrounding said openings, to hubs 3, provided with a central tapering bore adapted for the reception of a tapering sleeve 4.

The sleeves 4 encircle the shaft 1 within the hubs 3, and are provided with an outer externally threaded end for the reception of nuts 5 engaging thereon against the hubs 3 to draw said sleeves 4 tightly therein, and with longitudinally slotted ends to be forced into tight engagement with the shaft 1.

The end plates 2, are circular in shape, and are provided with continuously extending flanges 6, upon, and at right angles to the peripheral edge thereof, in the formation of which flanges, the material at the edge of the end plates 2, is stamped in semi-conical outwardly projecting crimps 7.

The periphery of my improved doffer is constructed by longitudinally extending circumferentially overlapping plates 8, connected at their ends upon the end plates 2 and supported intermediate said plates by circular supporting plates 9 having a circular edge flange to which said plates are riveted, and provided with an opening in the center, of the proper size through which the shaft 1 passes. In their overlapping relation, the plates 8 are provided with longitudinally extending parallel semi-cylindrical ribs 10 and 11 and with an upstanding flange forming a blade 12, which ribs 10 and 11 are respectively adjacent to said blade 12 and the opposite longitudinal edge of the plate. It will be evident that in forming these ribs, a corresponding depression in the opposite side will be formed. Thus plates 8 are overlapped to such a degree as to engage, with their depressions corresponding to ribs 10 adjacent their blades 12, the ribs 11 adjacent the edge of the adjoining plates, and are secured to the end plates 2 with their engaged ribs and depressions over each of the crimps 7 thereof, thus insuring an air-tight joint in order that the doffer when rotating, will not collect dirt or dust therein.

The blades 12 of the peripheral plates 8 are, as shown, provided with equidistantly spaced notches, recessed in the longitudinal edge thereof, and designed to aline with the saw blades of the gin saw, whereby the saw blades will not be harmed in case vibration of the saw cylinder causes the same to approach more closely my improved doffer.

From the foregoing, it will be readily seen that I provide a doffer which will be practically indestructible, which is air-tight, and which is provided with means whereby the same, when mounted closely adjacent but in non-contacting relation to a gin saw, and

rotated at a greater peripheral speed than said saw, will create a current of air sufficient to withdraw all cotton and lint from the blades thereof.

5 Having described my invention, I claim:

1. In a doffer comprising circularly flanged end plates, and longitudinal circumferentially overlapping plates having outstanding flanges, and secured at their ends to said end 10 plate flanges, said overlapping plates having means which relatively interlock with each other, and with portions of the flanges of said end plates, substantially as described.

2. A doffer comprising circularly flanged end plates, and longitudinal circumferentially overlapping plates secured at their ends to said end plate flanges in air-tight relation, and provided with longitudinal relatively 15 engaging elevations and depressions in their overlapping relation, and with outstanding 20

flanges forming generating blades, substantially as described.

3. A doffer comprising end plates having circular edge flanges provided with spaced crimped portions, and longitudinal circumferentially overlapping plates provided with longitudinal relatively engaging elevations and depressions in their overlapping relation and with outstanding flanges forming generating blades, said overlapping plates 25 30 being secured at their ends to the said end plate flanges with their engaged elevation and depressions fitting about the said crimped portions thereof.

In testimony whereof I affix my signature 35 in presence of two witnesses.

ARTHUR A. VARDELL.
